UNITED STATES PATENT OFFICE.

ALBERT WILLIAMS, OF HANNIBAL, NEW YORK.

MIDDLING-PURIFIER.

SPECIFICATION forming part of Letters Patent No. 268,762, dated December 5, 1882.

Application filed March 27, 1882. (No model.)

To all whom it may concern:

Be it known that I, ALBERT WILLIAMS, of Hannibal, in the county of Oswego and State of New York, have invented a new and useful Improvement in Middlings-Purifiers; and I do hereby declare that the following is a full and exact description of the same, reference being had to the accompanying drawings, and to the letters of reference marked thereon.

10 The invention hereinafter described and illustrated has reference to that class of machines known as "middlings-purifiers."

15 I will now proceed to give a full description of my apparatus, referring to each feature therein contained by means of letters marked on the accompanying sheets of drawings, said drawings forming a part of this specification, and representing, in—

20 Figure 1, a perspective view of the purifier; Fig. 2, a rear elevation of the same; Fig. 2', a longitudinal central vertical section on line *x x*, Fig. 2; Fig. 2'', a horizontal section on line *y y*, Fig. 3; Fig. 3, a view in detail of the distributing-table and its attachments; Fig. 4, a 25 view in detail of a deflector used in my construction; Fig. 5, a view in detail of the gates used; and Fig. 6, a view of one corner of the shaker-frame, showing the manner of connecting the end and side pieces of said frame.

30 The same letters refer to the same or corresponding parts throughout the several views.

In the drawings, A represents the shell of the machine, preferably rectangular, and composed of suitable frame-work, and so constructed that by the removal of several screws any one of its sides can be taken off, and thus provide ready access to the interior when desired. The part A', which covers the rear end of the machine at the exit of waste, can be adjusted at any angle to suit the requirements of the machine.

To the front end of the machine (see Fig. 1) are firmly secured the brackets or supports *a a'*, in which a shaft, B, has its bearings. This shaft, as shown, is provided at its center with a driving-wheel, *b*, and at each end with an ordinary fan-wheel, *M*, whose fans revolve in the fan-case C and convey air to the purifier through the medium of mechanism to be hereinafter referred to. The shaft B is also provided at suitable points with the eccentrics *b' b''*. Around these rings are placed the eccen-

tric-rods *c' c''*, which are connected at one end in any suitable manner to the set of perpendicular pitmen *d d'*, the other end of said pitmen 55 being firmly secured to a bar, *e*, which is situated between two extending arms, *e' e''*, of a vibrating frame, on which is placed the screen, hereinafter described.

By use of the mechanism and construction 60 thus far described it will be seen that upon the revolution of the shaft B motion is imparted to the distributing-table through the medium of the eccentrics *b' b''* and the pitmen *d d'*. Through the lower ends of these pitmen 65 is passed a rod which has secured to it two arms, which are pivoted at their other ends in slots made in the upper ends of another set of perpendicular pitmen, *g g'*, this rod and the arms secured thereto not being shown in the drawings. These pitmen *g g'* are connected at their 70 other or lower ends to the transverse rod *g''*. This rod *g''* is situated between arms *h h'*, which are secured on the under face of a vibrating bottom, hereinafter referred to. By this construction, upon the revolution of the shaft B motion is imparted through the medium of the 75 two sets of perpendicular pitmen to the distributing-table and the bottom of the purifier simultaneously.

To the main frame and at the points shown in Fig. 1 are securely fastened the brackets *i i'* and *j j'*, which serve as bearings for the rods *h* and *l*, respectively, and on these rods the two sets of pitmen *d d'* and *g g'* have their centers 80 or pivots.

The sides of the casing of the purifier are so constructed that they will project outwardly and form on each side thereof a longitudinal tapering tube, D. (Shown partly broken away in 90 Fig. 1 of the drawings.) These tubes are smallest at the rear end of the purifier, and at their largest ends are so constructed as to form casing C for the fans, which have their bearings on the shaft B. It is through these tubes D that air is 95 conveyed from the fans to the transverse tubes E E, &c., which are situated, as shown in drawings, at points between the distributing-table and the bottom of the machine, and which open into the tubes D. The amount of air to be admitted into these tubes E, or into any one of them, is regulated by a system of gates, F F, &c., there being one gate for each tube, the 100 number of tubes to be determined by the size

of the machine upon which they are used. These tubes E are placed at suitable distances from each other to allow the middlings to pass between them in falling from the screen to the bottom of the machine. In Fig. 1 of the drawings I have shown three of these tubes. Over the open tops of two of said tubes, as shown, I have placed a piece of bolt-cloth, m, which is secured in any desirable manner to said tube. 10 Over this bolt-cloth, as shown in the same figure, is placed the peculiarly-shaped deflector l, preferably of metal, the construction of said deflector also being shown in Fig. 4. As clearly shown in this latter figure, it is provided with sloping sides and on each of its ends with two downwardly-projecting arms, m' m² and m³ m⁴, by means of which it is secured to the side frame-work of the purifier, and along its upper edge with a slot, n, through which the 15 air forced into the tubes E escapes up to the screen. The object of providing these tubes E with these coverings is to prevent the middlings from falling on the bolt-cloth and preventing the air from escaping from the tubes. 20 The bottom of the machine is pivoted by means of the pitmen before described and two arms which are secured to said bottom and to the side of the purifier at points near its rear. Only one of these arms, which is marked o, is 25 shown in Fig. 1. This bottom slopes toward one side of the machine sufficiently to allow the middlings to escape therefrom after being purified.

In Fig. 3 I have clearly and in detail shown 30 the construction and arrangement of the shaker used in my construction. As shown in that figure, there is a rectangular frame, L, in which are cut the openings or recesses p, &c., for the purpose described hereinafter. This 35 frame L is intended to fit closely within the casing of the machine, in the sides of which casing there is a portion at r cut away to correspond with each of the recesses p, above mentioned. This latter construction is clearly 40 shown in Fig. 1. Within this frame L the screen-frame G, which is provided with the bolts s s s, &c., as shown, is placed, said bolts s passing through the recesses p, made in the frame L, as described. These bolts s are 45 prevented from leaving the screen-frame G by nuts s', and have placed on their opposite ends the rubber buffers s², which in their turn are held on the bolts by means of nuts s''. This screen-frame G is covered, as shown, with any suitable screen-cloth, s⁴, adapted to this purpose, said cloth being secured to the frame in any desirable manner. The frame L is pivoted in the machine by means of the pitmen d d', before referred to, and the arms y y. (Shown in 50 Fig. 2.) These arms y y are secured at their upper ends to the rod z, secured to the frame L, and at their lower ends to any convenient portion of the casing. Any sagging or giving in the cloth is immediately taken up by 55 the expansion of the rubber buffers s², and by the arrangement of said buffers on each side

of the frame, as shown, an equal strain is on the cloth from every side, and the size and shape of the meshes in said cloth maintained. Should the strain be from one side alone, the 70 shape and size of the meshes would be changed, and all advantage derived from stretching the cloth would be lost.

At the rear end of the purifier, as shown in Fig. 2, reacting hammers H H are suspended 75 in brackets H' H' by means of a rod, H². These are situated as shown, and project a sufficient distance from the end of the casing to allow free and easy movement of the hammers in striking against the ends of the frame 80 L. By the striking of these hammers against the frame L the concussion is received by the bolts s, and by them imparted to the entire cloth, which aids greatly in clearing the meshes of said cloth. 85

In Fig. 3 is shown a feeding device, which is designated by the letters I in the drawings. It is a V-shaped hopper, and is composed of two parts, I and I', and is secured to a cross-piece, v, secured to the frame L, as shown in 90 Figs. 1 and 3. The part I forms the back, sides, and bottom of the hopper, and is itself V-shaped, with its bottom resting upon the cross-piece v, as before mentioned. The part I' is perforated, as shown, with holes w w, and 95 fits closely into the part I, its lower edge resting upon the lower side thereof, and is also secured to the cross-piece v by means of wings u u' by means of screws, which are passed through the holes shown in said wings. The 100 part I is also fastened to the cross-piece v by means of screws passed through the bottom thereof, or it may be secured in any other desirable manner. The middlings are fed into the mouth of this hopper and by the motion of 105 the vibrating frame L are sifted through the holes w, and then pass to the distributing-cloth.

The operation of the machine is as follows, viz: The machine being set in motion by means of the necessary power applied to the shaft B 110 at b, the middlings to be purified are fed into the hopper I, and thence through the perforations w w to the screen s⁴, which is being vibrated by the pitmen d d', connected with the shaft B and operated by the eccentrics b' b'. 115 The middlings as they enter upon the screen sift through quite rapidly, while the coarser parts—such as the bran and brown speck—are prevented from going through the screen by the action of the wind, which is forced by the 120 wind-fans through the longitudinal tubes D into the transverse tubes E, and thence up against the under surface of the screen. The gates F F, &c., regulate to a nicety the amount of wind thus brought to bear under the screen, 125 and also the exact points of said screen against which the wind is to be directed. The coarser particles—such as the bran, &c.—are kept in continual agitation toward the tail end of the screen, and finally pass off over the end thereof, 130 while the finer portions of the middlings pass through the screen into the bottom of the ma-

chine, which is being vibrated by the pitmen *g g'*, from whence it escapes through the side thereof. The hammers *H H* act upon the screen-frame and greatly aid in clearing out 5 the meshes of the screen-cloth by knocking and jarring said vibrating frame.

Having thus fully described the several parts of my invention, what I claim as new therein, and desire to secure by Letters Patent, is—

10 1. In a machine for purifying middlings, the frames *G* and *L*, in combination with bolts *s* and rubber buffers *s'*, the parts arranged and operated as shown, and for the purpose set forth.

2. In a machine for purifying middlings, the 15 reacting hammers *H*, suspended as described and in combination with the vibrating frame *L*, the parts arranged and operated as described.

3. In a machine for purifying middlings, the deflectors *l* and tubes *E*, in combination with 20 gates *F*, tapering tubes *D*, and fans *M*, substantially as described.

This specification signed and witnessed this 6th day of March, 1882.

ALBERT WILLIAMS.
